UNITED STATES PATENT OFFICE.

EDMOND A. SALTER, OF CYPRESS, LOUISIANA, ASSIGNOR OF ONE-HALF TO CHARLIE M. PHARIS, OF NATCHITOCHES, LOUISIANA.

BOLL-WEEVIL EXTERMINATOR.

1,250,516.

Specification of Letters Patent. Patented Dec. 18, 1917.

Application filed January 10, 1917. Serial No. 141,653.

To all whom it may concern:

Be it known that I, EDMOND A. SALTER, a citizen of the United States, residing at Cypress, in the Parish of Natchitoches and 5 State of Louisiana, have invented certain new and useful Improvements in Boll-Weevil Exterminators, of which the following is a specification.

This invention relates to an improved boll 10 weevil exterminating machine and the principal object of the invention is to provide a machine of the character described in which the plants may be shaken or agitated to cause the boll weevils to drop from the 15 plants and to further provide improved means for removing the boll weevils from the ground and from the cotton plants, the weevil collecting portion of the machine including a suction tank for receiving the 20 weevils and an air pump for driving the weevils to the inlet nozzle of the suction tank, the air supply pipe of the pump leading from the tank to create a suction therein.

Another object of the invention is to so 25 construct this machine that the auxiliary frame carrying the air pump and weevil receptacle may be vertically adjusted to bring the nozzle of the blast pipe and suction pipe into the proper position with relation to 30 the ground.

This invention is illustrated in the accompanying drawings, wherein:—

Figure 1 is a view showing the improved machine in side elevation,

35 Fig. 2 is a view showing the machine in rear elevation,

Fig. 3 is a top plan view of the improved machine,

Fig. 4 is a view showing the machine in 40 vertical longitudinal section,

Fig. 5 is a perspective view of the nozzle operating device, and,

Fig. 6 is a longitudinal sectional view 45 through the weevil receptacle taken along the line 6—6 of Fig. 3.

This machine is provided with a tongue 10 having side bars or arms 11 and 12 extending rearwardly and terminating in depending standards 13 carrying bearings 14 50 for the axle or main drive shaft 15. This

axle 15 carries the supporting wheels 16 which are fastened upon the axle so that when the wheels rotate, the axle will be rotated with the wheels. In order to brace the standards 14 there has been provided 55 bracing bars 17 leading from the bearings 14 to the forward portions of the side bars 11 and 12. A driven shaft or pump actuating shaft 18 is rotatably carried by the side arms 11 and 12 and carries a large pulley 60 wheel 19 and a small pulley wheel 20, the small pulley wheel being positioned in alignment with the large pulley wheel 21 mounted upon the shaft 15 thus permitting rotary movement to be transmitted from the shaft 65 15 to the shaft 18 through the medium of the pulleys 20 and 21 and belt 22 passing around these pulleys. A clutch 23 is slidably mounted upon the shaft 15 and is engaged by latch lever 24 so that this clutch 70 may be brought into and out of engagement with the clutch 25 of the pulley 21 thus controlling the rotation of the pulley 21.

The auxiliary frame 26 is positioned within the main frame and has its arms mounted upon the axle 18 and is provided at its forward end with an eye 27 with which is connected the line 28 carried by the cam 29. This cam 29 is pivotally mounted in a slot 10' formed in the tongue 10 and is connected with the yoke 30 by means of a pin 31 so that when the shaft 32 with which the yoke is connected, is moved longitudinally of the machine, the cam will be rocked upon its pivot 29' and the auxiliary frame 75 vertically adjusted. This shaft 32 extends longitudinally of the frame and is provided at its rear end with a lever 33 by means of which it may be rotated or oscillated to actuate the nozzle operating mechanism to 80 be hereinafter described. A latch lever 34 is carried by the tongue 10 and is provided with an eye 35 which engages the reduced intermediate portion 36 of the shaft 32 and provides means whereby the shaft may be 85 moved longitudinally to rock the cam 29 vertically when the latch lever is moved. A sleeve 37 is mounted upon the shaft 32 to rotate with the shaft and carries a depending finger 38 which extends into the 90 100

opening 39 formed in the plate 40 extending from the bar or head 41 connecting the nozzle moving or actuating arms 42. This head 41 is slidably connected with the cross bar 43 by clamps 44 and when the shaft 32 is rotated or oscillated by means of the lever 33, the actuating bar will be moved transversely of the exterminating machine to guide the nozzles and cause the boll weevils 10 to be removed from the plants.

The auxiliary frame carries a rotary pump 45 provided with an actuating shaft 46 which carries a pulley 47 about which passes a driving belt 48 so that rotary motion can 15 be transmitted from the shaft 18 to the pump shaft 46 through the medium of the pulleys 24 and 47 and belt 48 passing around these pulleys. The flexible outlet pipe 49 for this pump terminates in a nozzle 50 positioned 20 opposite the inlet nozzle 51 of the flexible pipe 52 leading to the tank or weevil receptacle 53. This receptacle 53 is provided with a removable closure 54 carrying a wire cage 55 to receive the weevils and hold the same 25 against passage from the housing into the pipe 56 leading to the pump 45. It will thus be seen that when the pump is in operation, the air will be sucked through the pipe 52 into the housing 53 and through the pipe 30 56 into the pump from which it will be forced through the pipe 49 and out through the nozzle 50. This air blast will strike the plants thus driving the boll weevil over toward the nozzle 51 into which they would 35 be sucked and drawn up through the pipe 50 into the receptacle 53 where they would accumulate in the cage 55. It will thus be seen that there has been provided a boll weevil exterminator which can be drawn 40 across a field with the machine straddling a row and the boll weevil caused to drop from the plants through the operation of the collector, the auxiliary frame being adjusted vertically and the head 41 shifted so that 45 the nozzles will be held adjacent the plants to act upon the weevils with the blast from the nozzle 50 driving the weevils toward the nozzle 52 into which they will be sucked and drawn into the housing 53.

50 What is claimed is:—

1. A boll weevil exterminating machine comprising a main frame including a tongue and side arms extending from the tongue and terminating in depending arms having 55 bearings, a driving shaft rotatably mounted in the bearings, a driven shaft rotatably carried by the side arms, means for transmitting rotary movement from the driving shaft to the driven shaft, an auxiliary frame positioned within the main frame and pivotally mounted upon the driven shaft, means for releasably holding the auxiliary frame at an 60 adjusted angle, a cross bar carried by the auxiliary frame, nozzle engaging means

movably mounted upon the cross bar, actuating means for the engaging means carried by said tongue, an air pump carried by the auxiliary frame and including a driving shaft and an outlet pipe, means for transmitting rotary movement from the driven shaft to the pump shaft, a receptacle carried by the auxiliary frame and provided with an air outlet pipe forming an air inlet pipe for the pump, a closure for the receptacle, a perforated cage within the receptacle, and an air inlet pipe for said receptacle, the air inlet pipe of said receptacle and the air outlet pipe of said pump being provided with nozzles positioned in alinement and extending transversely of the machine. 80

2. A boll weevil exterminating machine comprising a main frame including a tongue and an axle constituting a driving shaft, a driven shaft carried by the main frame, an auxiliary frame pivotally mounted upon the driven shaft, a pump carried by the auxiliary frame, a receptacle carried by the auxiliary frame, a pipe leading from the receptacle to the pump, an air inlet pipe for said receptacle, terminating in a nozzle extending transversely of the frame, an air outlet nozzle for the pump terminating in a nozzle extending transversely of the frame and in alinement with the nozzle of the inlet pipe of said receptacle, a pump shaft for said 95 pump, means for transmitting rotary movement from the driving shaft to the driven shaft, means for transmitting rotary movement from the driven shaft to the pump shaft, means for vertically adjusting said auxiliary frame and releasably holding the same in an adjusted position, and plant actuating means carried by said auxiliary frame. 100

3. A boll weevil exterminating machine comprising a main frame including a tongue and a driving shaft, a driven shaft carried by the main frame, an auxiliary frame pivotally mounted upon the driven shaft, a cam carried by said tongue, a line connected with the cam and with the auxiliary frame, a shaft connected with said cam, means for moving said shaft longitudinally to move said cam and vertically adjust the auxiliary frame, a nozzle operator slidably connected with the auxiliary frame, a finger extending beneath the shaft and engaging the nozzle operator, means for oscillating the shaft to move said nozzle operator transversely of the auxiliary frame, a pump carried by the auxiliary frame and including a pump shaft, means for transmitting rotary movement from the driving shaft to the driven shaft, means for transmitting rotary movement from the driven shaft to the pump shaft, a receptacle, a pipe leading from the receptacle to the pump, an outlet pipe leading from the pump and terminating in an outlet nozzle, and an inlet pipe for said 115 120 125

receptacle provided with a nozzle in alignment with the nozzle of the outlet pipe.

4. A boll weevil exterminating machine comprising a main frame, a driving shaft carried by the main frame, a driven shaft carried by the main frame, an auxiliary frame pivotally mounted upon the driven shaft, a shaft carried by the main frame, means for vertically adjusting the auxiliary frame including a cam actuated through longitudinal movement of the shaft of said main frame, nozzle guiding means carried by said auxiliary frame, actuating means for the guiding means mounted upon the shaft 10 and moved to actuate the guiding means through oscillating movement of the shaft, a pump carried by the auxiliary frame and including a pump shaft and an outlet pipe, a receptacle carried by the auxiliary frame 15 and including an inlet pipe and a pipe leading to the pump, means for transmitting rotary movement from the driving shaft to the driven shaft, and means for transmitting rotary movement from the driven shaft 20 to the pump shaft.

5. A boll weevil exterminating machine comprising a main frame, a driving shaft carried by the main frame, a driven shaft carried by the main frame, an auxiliary frame pivotally mounted upon the driven shaft, nozzle guiding means slidably connected with the auxiliary frame, means for vertically adjusting the auxiliary frame including a cam carried by the main frame, a 30 shaft connected with the cam and provided with an actuating element engaging the guiding means, means for moving the shaft longitudinally to rock the cam and vertically adjust the auxiliary frame, means for oscillating the shaft to actuate the guiding means, a pump including a pump shaft, a receptacle having a pipe leading to the pump, means for transmitting rotary movement from the driving shaft to the pump 35 shaft, and pipes leading from the receptacle and pump and provided with aligned nozzles.

6. A boll weevil exterminating machine comprising a main frame including a driving shaft, a pivotally mounted auxiliary frame, a receptacle carried by said auxiliary frame, a perforated weevil container in said receptacle, an inlet pipe leading from said receptacle and terminating in a nozzle, a pump carried by said auxiliary frame including a pump shaft, means for transmitting rotary movement from the driving shaft to the pump shaft, an outlet pipe leading from the pump and provided with a nozzle in alignment with the nozzle of the inlet pipe of said receptacle, a pipe leading from said receptacle to said pump for conducting air from said receptacle to said pump, nozzle guiding means carried by said auxiliary frame, means for vertically adjust-

ing the auxiliary frame, and actuating means for the guiding means.

7. A boll weevil exterminating machine comprising a main frame, a driving shaft carried by the main frame, an auxiliary frame pivotally mounted, a pump carried by the auxiliary frame and provided with a pump shaft, means for transmitting movement from the driving shaft to the pump shaft, an outlet pipe leading from said pump, a receptacle carried by the auxiliary frame, a pipe leading from the receptacle to the pump, an inlet pipe leading from the receptacle and extending in operative relation to the outlet pipe of said pump, nozzle guiding means carried by said auxiliary frame, and means for vertically adjusting said auxiliary frame including means for actuating the guiding means.

8. A boll weevil exterminating machine comprising a main frame, an auxiliary frame, a weevil receptacle carried by the auxiliary frame, a pump carried by the auxiliary frame and having an inlet pipe communicating with the weevil receptacle for creating a suction therein, means for transmitting movement from the driving shaft to the pump for actuating the pump from the driving shaft, a cross bar carried by the auxiliary frame, a nozzle guide slidably mounted upon the cross bar and provided with depending plant engaging arms, means for vertically adjusting the auxiliary frame including an actuating bar having an arm extending therefrom to engage said guiding means, means for moving said bar longitudinally to vertically adjust the auxiliary frame, means for rotating said bar to oscillate the arm extending therefrom and move the guiding means transversely of the auxiliary frame, an air inlet pipe extending from said receptacle, and an air outlet pipe extending from said pump in operative relation to the inlet pipe for directing a blast across the space between the air outlet pipe and air inlet pipe and drive the weevils into the inlet pipe.

9. A boll weevil exterminating machine comprising a main frame, an auxiliary frame carried by said main frame, a weevil receptacle carried by the auxiliary frame, nozzle guiding means carried by the auxiliary frame, a pump carried by the auxiliary frame and having communication with said receptacle, means for vertically adjusting said auxiliary frame including means for actuating the nozzle guiding means, and means for operating said pump.

10. A boll weevil exterminating machine comprising a main frame, an auxiliary frame carried by the main frame, nozzle guiding means carried by the auxiliary frame, means carried by the main frame for vertically adjusting the auxiliary frame, and

actuating the nozzle guiding means, suction operated weevil collecting means carried by said auxiliary frame and including a weevil receptacle and a pump communicating therewith, and means carried by the main frame for actuating said pump.

In testimony whereof I affix my signature in presence of two witnesses:

EDMOND A. SALTER.
